UNITED STATES PATENT OFFICE.

ARVID EK, OF PORTLAND, MAINE, ASSIGNOR TO BROWN COMPANY, OF PORTLAND, MAINE, A CORPORATION OF MAINE.

PAPER TOWEL.

Application filed July 16, 1920. Serial No. 396,784.

My invention relates to new and useful improvements in paper towels, and more particularly to the manner of folding the individual towels and interfolding adjacent 5 towels when in package form.

The principal object of the invention consists in folding and interfolding the towels so that a plurality of towels may be placed in a cabinet and one towel withdrawn at a 10 time.

A further object consists in folding the individual towels in such a manner that there are a multiplicity of folds, intermediate the ends, and the end flaps extend in opposite 15 directions.

Another object resides in folding the towels so that the end flaps will be of less width than the remaining folded portions in order 20 that the towels may be easily assembled and interfolded.

With these and other objects in view my invention consists in the novel details of construction and arrangement of parts which will be more clearly understood from the 25 following specification and drawings, in which:—

Figure 1 is a top plan.

Figure 2 is an end view of a package of towels.

Figure 3 is an enlarged end view showing the manner of interfolding the towels.

In the drawings, 1 indicates a paper towel having a multiplicity of folds 2 intermediate its ends, said folds forming end flaps 3 and 4 of less width than the remaining folded portions of the towel. As shown, the end flaps extend in opposite directions, and while various numbers of folds may be made, I find that four folds very nicely answer 35 the purpose and form a towel of convenient size.

In use, a number of towels will be assembled into package form so that they may be readily inserted into a dispensing cabinet for withdrawing one at a time. When assembled the end flaps 3 and 4, of adjacent towels, will interfold so that as one towel is withdrawn from the cabinet it will bring the flap of the next towel into proper position to be grasped.

I lay particular advantage upon having the end flaps of less width than the remaining folded portions, and in having them extending in opposite directions. By having 50 the flaps extending in opposite directions no

matter in what position the towels might be, they may be easily assembled and interfolded. By having the end flaps of less width than the remaining portions, the end flaps may be easily located for assembling 60 into package form and the end flap of one towel easily directed into interfolded position with the flap of another towel. At the same time the narrower end flaps will allow for the interfolding of towels in such a manner that straight vertical edges will be provided and there will be no bulging or unevenness at the point of interfolding. The end flaps may be easily drawn through the 65 openings in the dispensing cabinet, while the wider portions will be supported on the bottom of the cabinet.

Towels, as above described, may be used with various forms of dispensing cabinets, having a discharge opening at the bottom, 70 sides or top and while I have described the preferred form of my invention, it will be understood that such changes may be made as will fall within the scope of the appended 75 claims.

Having fully described my invention, what I claim as new and desire to secure by Letters Patent is:—

1. A package of paper towels comprising a plurality of towels of uniform size and shape, each of said towels having a multiplicity of folds intermediate its ends, the end flaps of each towel extending in opposite directions and of less width than the remaining portions, said end flaps extending in 80 opposite directions and being of equal width allowing interfolding of adjacent towels no matter what faces of the towels may be placed together, and being of less width than the remaining folded portions allowing easy 85 guiding and interfolding of the end flaps of adjacent towels.

2. A package of paper towels comprising a plurality of towels of uniform size and shape, each of said towels having a multiplicity of folds intermediate its ends, the end flaps of each towel being of less width than the remaining folded portions and the end flaps of adjoining towels interlocking, substantially as and for the purpose de- 90 scribed.

In testimony whereof I hereunto affix my signature.

ARVID EK.
